CLAIM

The ornamental design for an alcohol stove, as shown and described.

DESCRIPTION

FIG. 1 is a front, left and top perspective view of an alcohol stove showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, left and top perspective view of the alcohol stove of FIG. 1, shown in condition of use.

The broken lines in the figures illustrate portions of the alcohol stove that form no part of the claimed design.

1 Claim, 9 Drawing Sheets
